[57] CLAIM

The ornamental design for a floating gold dredge, as shown.

DESCRIPTION

FIG. 1 is a right front perspective view of the floating gold dredge, showing my new design;

FIG. 2 is a top plan view;

FIG. 3 is a side elevational view, the other side elevational view being substantially a mirror image thereof;

FIG. 4 is a bottom plan view;

FIG. 5 is a front end elevational view; and,

FIG. 6 is a rear end elevation view.
